CLAIM

The ornamental design for a vehicle bow top clip as shown and described.

DESCRIPTION

FIG. 1 is a front perspective view of the vehicle bow top clip of the present invention;

FIG. 2 is a front, top perspective view thereof;

FIG. 3 is a back, top perspective view thereof;

FIG. 4 is a front view thereof;

FIG. 5 is a back view thereof;

FIG. 6 is a left side view thereof;

FIG. 7 is a right side view thereof; and,

FIG. 8 shows a front perspective view thereof, shown in a condition of use.
The broken lines in FIG. 8 depict environmental structure that forms no part of the claimed design.**1 Claim, 8 Drawing Sheets**FIG. 1

FIG. 2

FIG. 3

FIG. 4

FIG. 5

FIG. 6

FIG. 7

FIG. 8
